UNITED STATES PATENT OFFICE.

WILLIAM W. WHITAKER, OF GLOVERSVILLE, NEW YORK, ASSIGNOR OF ONE-HALF TO DANIEL S. HULETT, OF SAME PLACE.

MITTEN.

SPECIFICATION forming part of Letters Patent No. 241,837, dated May 24, 1881.

Application filed April 15, 1881. (No model.)

To all whom it may concern:

Be it known that I, WM. W. WHITAKER, a citizen of the United States, residing at Gloversville, in the county of Fulton and State of New York, have invented certain new and useful Improvements in Mittens; and I do hereby declare the following to be a full, clear, and exact description of the invention, such as will enable others skilled in the art to which it appertains

10 to make and use the same, reference being had to the accompanying drawings, and to letters or figures of reference marked thereon, which form a part of this specification.

My invention consists of a mitten having a 15 single-ply back and two-ply wrist knit in a continuous piece, with selvages; and also in a leather palm having the edge of the leather overstitched or overcast before being attached to the mitten.

20 In the accompanying drawings, Figure 1 is the leather palm and border-pieces, with their edges overstitched, ready to be attached to the mitten. Fig. 2 is a back view of the complete mitten. Fig. 3 is a longitudinal section on the 25 line $x x$, Fig. 2.

In the manufacture of my improved mitten, I first knit a blank for the single-ply back and

two-ply wrist in a continuous piece, and then invert the wrist, as shown in Fig. 3, the single-ply back being shown at A, Fig. 2, the wrist at B, 30 with the inverted part at C. Then I cut the palm-leather D and border-strips E and F, and overstitch or overcast the edges, as seen at G. This overstitching or overcasting prevents the edge of the leather from stretching, and also 35 gives a neat finish to the mitten.

The palm-leather may have a lining, H, Fig. 3, and a flap, I, may be attached to the wrist, to aid in pulling on the mitten and prevent stretching the knit wrist. 40

Having described my invention, what I claim is—

1. A mitten having a single-ply back and two-ply wrist knit in a continuous piece, with selvages, substantially as set forth. 45
2. In a mitten having a leather palm, the overstitched or overcast edge, substantially as and for the purposes set forth.

In testimony whereof I affix my signature in presence of two witnesses.

WILLIAM W. WHITAKER.
